OVER-WIND PREVENTION DEVICE FOR SPRING MOTORS

Filed March 2, 1935

FIG. 1.

UNITED STATES PATENT OFFICE

2,060,268

OVER-WIND PREVENTION DEVICE FOR
SPRING MOTORS

Joseph Vass, Revere, Mass., assignor of one-fourth to Joseph Bear, Wakefield, and one-fourth to Samuel G. Sloane, Atlantic, Mass.

Application March 2, 1935, Serial No. 9,116

3 Claims. (Cl. 185—43)

My invention consists in a new and useful improvement in over-wind prevention devices for spring motors, and is designed more particularly to provide a mechanism for stem-winding watches whereby the winding stem will be disconnected from the winding pinion, so soon as the main spring has become wound to the desired degree. The particularly novel and useful feature of my invention is the combination of an improved shipping lever, for disconnecting the winding stem, with an entirely novel reciprocating actuating arm for operating the shipping lever. This novel form of arm is actuated, to co-act with the shipping lever, by a direct mechanical connection with the arbor of the main spring, and is restored to its normal inoperative position by means of its resilient mounting.

While I have illustrated in the drawing filed herewith and have hereinafter fully described one specific embodiment of my invention, it is to be distinctly understood that I do not consider my invention limited to said specific embodiment, but refer for its scope to the claims appended hereto.

25 In the drawing:

Fig. 1 is a top plan view of a watch, the dial-plate removed, showing the winding mechanism in operative position.

30 Fig. 2 is an enlarged vertical section on line 2—2 of Fig. 1.

Fig. 3 is a view similar to Fig. 1, showing the winding mechanism in inoperative position.

35 Fig. 4 is an enlarged vertical section on line 4—4 of Fig. 3.

40 As illustrated in the drawing, the watch provided with my improvement has the ordinary winding stem 1 with usual sleeve 2 carrying the hand-setting pinion 3 and clutch member 4 co-acting with its clutch member 5 on the winding pinion 6 which is connected by the usual gear train with the main-spring arbor 7 to which the inner end of the main-spring 8 is fixed, its outer end being attached to the barrel 9 in the usual way.

45 Above the barrel 9, the top plate 10 has a suitable aperture 11, and adjacent thereto the recess 12 in which is adjustably mounted the block 13 by bolts 14 tapped into the plate 10, passing through slots 15 in the block 13 and having heads 16 received into recesses 17 in the block 13. On its outer edge, the block 13 has an inclined shoulder 18 with which co-acts the inclined head 19 of a setting bolt 20 tapped in the plate 10.

50 Extending from the block 13 and positioned

5 in the aperture 11 is the spring-arm 21 carrying the annular plate 22 with ribs 23. This plate 22 is disposed concentrically with the arbor 7 and there projects through the plate 22 the threaded post 24 concentrically mounted on the arbor 7. Threaded upon this post 24 there is the circular disc 25 having a diameter slightly greater than the orifice 26 in the plate 22, and provided with a series of holes 27 through one of which loosely passes the post 28 tapped into the 10 barrel 9.

Extending from the plate 22 there is the rigid arm 29 having the inclined shoulder 30.

15 Suitably pivoted to the plate 10 between the sleeve 2 of the winding stem 1 and this arm 29, there is the shipping lever 31 having its end 32 received in the annular groove 33 of the sleeve 2 and its tail 34 so disposed that its inclined shoulder 35 co-acts with the inclined shoulder 30 of the arm 29. The lever 31 has the spring 36 to 20 rock the lever 31 to hold the sleeve 2 in such a position as normally to inter-lock the clutch members 4 and 5.

From the foregoing description of the details of construction of my device, its use and operation will be obvious. Since the spring 36 causes the shipping lever 31 normally to hold the clutch members 4 and 5 in engagement, it will be seen that rotation of the winding stem 1, through its sleeve 2, clutch members 4 and 5, winding pinion 6 and its gear train, will cause rotation of the arbor 7, thus winding up the main-spring 8. This rotation of the arbor 7 rotates the post 24 on the arbor 7, and since the post 28 passing through the disc 25 prevents rotation of the 30 disc 25, the rotation of the post 24, on which the disc 25 is threaded, causes the disc 25 to travel downwardly toward the plate 22. The parts are so designed and related that when the arbor 7 has been rotated sufficiently to wind the main-spring 8 to the desired degree, the disc 25 has been brought into contact with the plate 22 and has depressed the plate 22, against the influence of the spring-arm 21, and the plate 22 has depressed its associated arm 29 so that its inclined shoulder 30 co-acts with the inclined shoulder 35 of the tail 34 of the shipping lever 31, so that the lever 31 is rocked, thereby causing the sleeve 2 to move the clutch member 4 out of engagement with the clutch member 5, 40 thus disconnecting the winding stem 1 from the winding pinion 6, and thereby preventing further winding of the main-spring 8.

45 It is obvious that as the barrel 9 is rotated, under the influence of the main-spring 8 as the 50 55

watch is running, the post 28 mounted upon the barrel 9 causes the disc 25 to rotate about the post 24 which is now held stationary by the ordinary action of the pawl-controlled gear train. 5 Thus it is seen that the disc 25, threaded on the post 24, is caused to travel outwardly away from the plate 22. As soon as pressure from the disc 25 is removed from the plate 22, the spring action of the spring-arm 21 causes the plate 22 to move 10 outwardly and carry with it the arm 29, causing the release of the shipping lever 31, which is restored to its normal position by action of the spring 36, thus connecting the clutch members 4 and 5 and rendering the winding mechanism 15 again operative.

It is to be noted that I have designed and related the parts in such a way that while the winding mechanism is not disengaged until the completion of the desired amount of winding, the 20 mechanism is re-engaged after a very slight degree of unwinding of the main-spring 8. In this way, I have insured that the proper degree of tension will be put upon the main-spring, and no more, and also that the main-spring may be 25 re-wound, after a very short period of unwinding, and this re-winding will restore the main-spring to its proper degree of tension, and no more.

It is to be noted that by providing a plurality of holes 27 in the disc 25, it is possible to adjust 30 the disc 25 relative to the post 24, in the initial assembly of the parts, so as to secure the proper distance of travel of the disc 25 to properly operate the arm 29 and lever 31.

It is also to be noted that by means of the 35 setting bolt 20, the block 13, plate 22 and arm 29 may be properly adjusted to secure the desired relation between the shoulders 30 and 35. When the block 13 has been properly adjusted, it is fixed in position by the bolts 14.

40 Having described my invention, what I claim is:

1. The combination, with the main-spring of a spring motor, the winding pinion, clutch and winding stem, of a shipping lever adapted to engage and disengage the clutch; a rigid arm co-acting with said lever to cause it to function; a 45 plate from which said rigid arm is extended; a

spring-arm from which said plate is extended; and means actuated by the arbor of the main-spring and adapted to move said plate against the force of the spring-arm to cause said rigid arm to actuate the shipping lever. 5

2. The combination, with the main-spring of a spring motor, the winding pinion, clutch and winding stem, of a shipping lever adapted to engage and disengage the clutch; a rigid arm co-acting with said lever to cause it to function; 10 a plate on which said rigid arm is mounted; a spring-arm on which said plate is mounted; a threaded post on the arbor of the main-spring; a second plate threaded on said post and having an orifice; and a second post on the barrel of the main-spring passing loosely through said orifice, the parts being so related that the second plate is caused to travel in one direction by rotation of the arbor and in the other direction by rotation 20 of the barrel, and to engage the first plate to move it against the force of the spring-arm to cause said rigid arm to actuate the shipping lever. 15

3. In an over-wind prevention device for watches, the combination of a winding stem having a clutch member; a winding pinion having a clutch member with which the stem clutch member co-acts; a pivoted lever having a finger at one end to bring the stem clutch member into and out of engagement with the pinion clutch member, and having a beveled shoulder on its other end; a spring disposed against said lever to cause the clutch members to engage normally; an arbor on which the main-spring is mounted and with which the winding pinion is connected by a gear train; a spring barrel with which the main-spring is connected; a threaded post on said arbor; a plate threaded on said post and having an orifice; a post on said barrel passing loosely through said orifice; a resiliently mounted plate disposed in the path of travel of said first mentioned plate; and an arm on said second plate having a beveled shoulder to co-act with the beveled shoulder on the lever to move said lever against the impulse of said lever-spring to cause the clutch members to disengage. 25 30 35 40 45
